UNITED STATES PATENT OFFICE.

ALVA W. WOODWARD AND MAX C. KUHN, OF AKRON, OHIO, ASSIGNORS TO THE FIRE-STONE STEEL PRODUCTS COMPANY, OF AKRON, OHIO, A CORPORATION OF OHIO.

DIE OR PUNCH MOUNTING.

Application filed July 28, 1925. Serial No. 46,575.

This invention relates to mountings for dies or punches in punch presses whereby the die and punch will be relatively adjustable into proper relation to the work and to each other.

The chief object of the invention is to provide an improved mounting for either dies or punches permitting universal adjustment thereof within certain limits on the platens 10 of the press.

The foregoing and other objects are obtained in the rim press illustrated in the accompanying drawings and described below. It is to be understood that the invention is 15 capable of use in punch presses generally and is not limited to the press here described.

Of the accompanying drawings,

Figure 1 is a front elevation partly in section of a press embodying the invention: 20 Figure 2 is a transverse vertical section therethrough on line 2—2 of Figure 3; and Figure 3 is a plan thereof.

Referring to the drawings, 10 represents a conventional lower platen and 11 a conventional upper platen of a rim punching press. Secured on the platen 10 is a die block 12 seated in a longitudinal groove 13 formed in the surface of the platen. The walls 14, 14 of the groove are inclined outwardly and the 25 longitudinal edges 15, 15 of block 12 are inclined inwardly. For securing the block in place, wedge bars 16, 16 are provided and are arranged between the adjacent walls 14 and edges 15, screws 17, 17 extending through 30 the bars and threaded into the platen 10, being provided to wedge block 12 into determinate positions in groove 13. By the arrangement described, the block 12 may be moved in groove 13 longitudinally to any desired 35 longitudinal position and it may be adjusted transversely of groove 13 by relative adjustment of wedge bars 16 as will be clearly understood.

A similar mounting to that described above 40 may be used for securing a punch in place. In the illustration, however, the platen 11 has formed therein a groove 18 in which a punch block 18^a is secured by a wedge bar 19 cooperating with an inclined wall 20 of

groove 18 and an oppositely or reversely inclined edge 21 on block 18^a, bar 19 being actuated by screws 22, 22. Thus block 18^a is longitudinally adjustable in a similar manner to block 12 but is not transversely adjustable, the relative adjustment of block 12 50 transversely with respect to block 18^a being usually sufficient to properly align the punches and dies.

It will appear from the foregoing that a simple but effective mounting for dies or punches has been provided. Modifications 55 of the invention may be resorted to without departing from the spirit thereof or the scope of the appended claims.

What is claimed is:

1. A mounting for a die or punch comprising a platen formed with a longitudinal groove having inclined side walls, a block seated in the groove formed with reversely inclined longitudinal edges, said block being movable transversely and longitudinally in 60 said groove, wedge bars adapted to fit between adjacent side walls and edges, and means for urging each wedge bar inwardly of the groove.

2. A mounting for a die or punch comprising a platen formed with a longitudinal groove having inclined side walls, a block seated in the groove formed with reversely inclined longitudinal edges, wedge bars 70 adapted to fit between adjacent side walls, and means for urging each wedge bar inwardly of the groove.

3. A mounting for a die or punch comprising a platen formed with a longitudinal groove having inclined side walls, a block seated in the groove formed with reversely inclined longitudinal edges, said block being movable transversely and longitudinally in 75 said groove, wedge bars adapted to fit between adjacent side walls and edges, each wedge bar being provided with one inclined wedge face cooperating with an inclined side wall of the groove and another inclined wedge face cooperating with a reversely inclined longitudinal edge of the block, and means for urging each wedge bar inwardly 80 of the groove, whereby inward movement of 90

one wedge bar and outward movement of the other wedge bar will cause a transverse adjustment of said block.

4. In a punch press, the combination of 5 platen members relatively movable toward and from each other, a punch block mounted on one platen, a die block mounted on the other platen, one of said blocks being mount-

ed in a groove in its supporting platen, and means for permitting longitudinal and transverse adjustment of the latter block, comprising a pair of bars each having a wedge surface and cooperating with wedge surfaces on opposed sides of said latter block.

ALVA W. WOODWARD.
MAX O. KUHN.
